UNITED STATES PATENT OFFICE

SAMUEL I. COLE, OF BROOKLYN, NEW YORK

DESIGN FOR A CONDENSER CASING

Application filed December 19, 1929. Serial No. 33,850. Term of patent 7 years.

To all whom it may concern:

Be it known that I, SAMUEL I. COLE, a citizen of the United States, and residing at Brooklyn, county of Kings, and State of New York, have invented a new, original, and ornamental Design for Condenser Casing, of which the following is a specification, reference being had to the accompanying drawings, forming part hereof, and in which

Fig. 1 is a perspective view of a condenser casing showing my new design,

Fig. 2 is a top plan view thereof,

Fig. 3 is a side elevational view thereof, and

Fig. 4 is an end elevational view thereof. The condenser casing of the present invention comprises a flat generally rectangular slablike body presenting in plan view a pair of generally semi-circular projections adjacent opposite ends of and substantially tangential to one side only of the rectangular body, the casing including perforations arranged substantially within the confines of the respective projections.

I claim:

The ornamental design for a condenser casing substantially as shown and described.

SAMUEL I. COLE.
